UNITED STATES PATENT OFFICE.

EMIL GRIMSRUD, OF ANTELOPE, MONTANA.

PLOW.

Application filed January 31, 1920, Serial No. 355,314. Renewed June 28, 1922. Serial No. 571,475.

To all whom it may concern:

Be it known that I, EMIL GRIMSRUD, a citizen of the United States, residing at Antelope, in the county of Sheridan and State of Montana, have invented certain new and useful Improvements in Plows, of which the following is a specification.

This invention relates in general to agricultural implements and has particular reference to a plow.

One object of this invention is the production of a device which is in the nature of an addition to my prior Patent Number 1,253,961, relating to plows, for the purpose 15 of increasing the efficiency of operation thereof.

Another object of this invention is the production of an attachment for plows wherein the construction is so arranged 20 that the plow beam is pivotally and yieldably mounted upon the main frame so that when the plow becomes automatically broken upon striking an obstruction, the beam is elevated to allow the plow to snap back into an operative position and then at a predetermined interval thereafter the beam will be released to allow the plow 25 again to move down into operative engagement with the ground.

Another object of this invention is the production of an attachment for plows wherein the plow beam has a gage wheel standard pivoted thereon while means are provided upon the main frame of the device 30 which extend to and coact with the gage wheel standard so that automatically the mechanism will be actuated for elevating the outer end of the plow standard and subsequently allow the outer end to then be 35 lowered.

Another object of this invention is the production of means which may be either automatically thrown into an operative position or manually actuated for assuming 40 this condition whereby the gage wheel standard may be moved to cause the gage wheel to support the weight of the plow and plow beam, either when necessary or desired.

One practical form of construction and assembly of the present invention will be

hereinafter described and is illustrated in the drawings, in which—

Figure 1 is a top plan view of the entire device in condition for use, a portion 55 of a lever being shown in section.

Figure 2 is a side elevation of a plow beam and connections thereof, with the main frame of the device being shown in section.

Figure 3 is an enlarged fragmentary side elevation of the plow beam and operating mechanism coacting therewith.

Figure 4 is an enlarged fragmentary detail sectional view of a part of the device, 65 disclosing specifically the construction of the means connecting the coulter wheel standard to the mechanism which is either automatically or manually actuated for causing a swinging of the coulter wheel 70 standard as will be hereinafter explained.

Figure 5 is an enlarged fragmentary sectional view taken on the line 5—5 of Figure 1.

Figure 6 is a rear elevation of the device shown in Figure 5.

Figure 7 is an enlarged fragmentary sectional view taken on the line 7—7 of Figure 2.

Figure 8 is a sectional top plan view of a portion of the device, taken on the line 80 8—8 of Figure 2.

Figure 9 is a side elevation of a certain cam wheel used in this invention.

Figure 10 is a top plan view of the device shown in Figure 9.

Figure 11 is a fragmentary sectional view through a portion of the device.

Figure 12 is an enlarged sectional view taken on the line 12—12 of Figure 11.

Figure 13 is a rear elevation of the attachment to the rear end of the plow beam,

Figure 14 is a sectional view through a form of separable plow point and mold board used in connection with the present invention.

Figure 15 is a fragmentary sectional view of the device shown in Figure 14 with the sections disassembled.

Figure 16 is a side elevation of a certain locking pin and lever used in connection 100 with the device shown in Figure 14.

In the preferred embodiment of the pres-

ent invention, about to be described, the frame of the device comprises side bars 20 a front bar 21 and a rear bar 22, the rear bar having a base flange 23 and it will further be noted, by referring to Figure 1 that this rear bar 22 extends obliquely. Thus one of the side bars 20 is longer than the remaining side bar.

Supporting wheels 24 are mounted on 10 stub axles 25 which are connected by plates 26 to supporting standards 27 through the medium of spindles 28 to the side bars 20 of the frame. The drive wheel 29 is keyed upon an axle 30 having a sprocket 31 thereon, the axle 30 in turn being connected by a plate 32 to the frame, as shown in Figure 1. Clevis plates 33' are connected to the front bar 21 and thus it will be seen that draft means may be applied to the frame to 15 pull the same forwardly in view of the fact that the frame is mounted upon the wheels 24 and 29.

An obliquely extending bar 33 is mounted upon the frame as shown in Figure 1, while 25 braces 34 are connected to the rear bar 22 of the frame and the obliquely extending bar 33. A shaft 35 is journaled in one of the side bars 20 and in one of the braces 34 and has a sprocket 36 upon its outer end. A 30 sprocket chain 37 passes about sprocket 31 and sprocket 36 so that as the drive wheel 29 rotates, rotary motion will be continually imparted to the shaft 35. A second shaft 38 is journaled in the braces 34 and has a sprocket 39 upon one end thereof, around 35 which passes a chain 40, this chain passing around a similar sprocket 41 keyed upon the shaft 35. Thus it will be seen that as the shaft 35 is rotated, continuous rotary motion will be imparted to the shaft 38 upon 40 which is mounted a ratchet wheel 42, whereby continuous rotary motion will be imparted to the ratchet wheel 42, for purposes to be hereinafter apparent.

45 The plow beams supporting bracket comprises a body 43 which may be secured in any desired or approved manner upon the rear bar 22 of the frame. This bracket body 43 has a lip 44 extending from one end, 50 while a projection 45 extends from the opposite end thereof parallel to the lip 44, the projection 45 terminating in an inwardly extending foot 46. The plow beam 47 is connected by a bolt 48 pivotally and somewhat 55 loosely with the lip 44. A brace 49 is fixed as shown at 50 upon the plow beam 47 intermediate its ends, while this brace 49 is likewise provided with a foot 51 bearing normally upon the foot 46 of the bracket. A 60 bolt 53 passes through the feet and has a coiled spring 54 thereon the strength of which normally holds the foot 51 in engagement with the foot 46. Accordingly, when side strain is brought to bear upon the plow beam, it may swing slightly to one side since

the foot 51 may draw upon the bolt, against the tension of coiled spring 54 thus causing the foot 51 to move away slightly from foot 46 to allow the lateral movement of the plow beam at its outer end, although as soon as 70 this stress or strain is removed, the tension of the spring will be sufficient to return the foot 51 to its normal position.

The plow beam 47 has a pair of parallel strips 55 secured to its rear end, these strips 75 being in a sense an extension of the plow beam. These strips, therefor, receive the upper end of the plow standard 56 which is pivoted thereon by the pivot pin 57. An arm 56' extends from the upper end of the plow standard as shown in Figure 3, while a plow indicated at P is mounted upon the lower end of the standard 56. It should be mentioned that the particular part of the device now being described is referred to very particularly in the prior Patent Number 1,253,961. The standard 58 pulled by the spring 59 in one direction has its nose 60 engaging under the forward end of the arm 56' of the plow standard 56. A retaining claw member 61 is pivoted upon the parallel strips 55 of the plow beam 47 and engages the standard 58 within the notches thereof when the device is in a completely set condition to hold the standard 58 from being accidentally 95 moved. The trigger tube 62 engages with the base of the standard 58 and it is obvious this trigger tube will be forced forwardly when the plow P strikes an obstruction and the connection is broken, since the standard 100 56 swings rearwardly to cause the arm 56' to swing the standard 58 against the tension of the spring 59, whereby the lower portion of the standard 58 will be swung somewhat counter-clock-wise to push the trigger tube 105 61 forwardly for a purpose yet to appear.

A gage wheel 63 is rotatable upon the lower end of the gage wheel standard 64, this standard 64 being received upon the outer end of a hollow shaft 65 as shown in Figs. 110 3 and 11. This hollow shaft 65 extends transversely through the plow beam 47 and is rotatably supported. A trigger stem 66 is receivable in the rear portion of the trigger tube 62 and this stem 66 passes into a bore 115 67 in the rear end of the plow beam 47. This trigger stem 66 is connected as shown at 68 to a crank shaft 69 carried within the hollow shaft 65. This crank shaft 69 has an angular finger 70 at its outer end projecting to 120 one side of the hollow shaft 65 as shown clearly in Figures 3 and 11.

A hollow channel bar 71 has its rear end pivoted as at 72 to the gage wheel standard 64. The forward end of this channel bar 71 125 is pivotally mounted as shown at 72 upon an actuating lever 73 which is pivotally mounted upon the shaft 38 as shown clearly in Figure 7. It will be noted that this actuating lever 73 is bifurcated as shown at 74 130

to receive the forward end of the channel bar 71 therethrough. This channel bar, therefor, connects the actuating lever 73 to the standard 64 so that as the lever 73 is pulled forwardly it will necessarily cause the channel bar 71 to pull forwardly on the standard 64 to cause the gage wheel 63 to be moved forwardly and support the entire weight of the plow beam 47 with all attachments thereof including the plow P.

A slide 75 is reciprocally mounted within the channel bar 71, this slide being held from displacement by a slot and pin arrangement shown at 76 or by any other suitable means. It will be noted that the channel bar 71 is provided with a slot 77 contiguous to its rear end, through which extends the finger 70 of the crank shaft 69. This finger passes through an aperture 78 formed in the slide 75 so that as this finger is actuated, as will be hereinafter explained, the side may be moved rearwardly, although the slide is normally held in a forward shifted position and the finger 70 is normally held to slant forwardly by a coiled spring 79 engaged with the finger and with the channel bar as illustrated clearly in Figure 2. The forward end of this slide is provided with a head 80 in the rear of which is formed ratchet teeth 81. A suitable spring pressed latch 82 is pivoted upon the channel bar 71 and is adapted to engage the ratchet teeth 81 for holding the slide in a retracted position at certain times, as will be hereinafter apparent.

A ratchet dog 83 is pivoted within the bifurcation 74 of the actuating lever 73 and has a guide strip 84 extending above the upper surface thereof as shown in Figure 4. This ratchet dog 83 has a tail 85 which is carried under the spring pressed catch 82 as shown in several figures of the drawing.

A pair of parallel quadrants 86 are carried upon the frame upon opposite sides of the actuating lever 73 as shown in Figures 7 and 8. A hand lever 87 is pivoted upon the shaft 38 upon one side of one quadrant as shown. A housing 88 is carried upon the lever 87 and overhangs the quadrants 86. A detent plate 89 is movable through the housing 88 and may be actuated by the grip 90 and connecting strand 91 as shown in Figure 2. It will be noted that the detent 89 is carried in the rear of actuating lever 73, and that it may be lifted by moving the grip 90 toward the handle of the hand lever 87, so as to move out of engagement with the quadrant 86 to allow the hand lever to be swung as may be desired, as may be herein-after set forth.

A cam wheel shaft 92 is rotatable upon the frame extending upon the flange 23 of the rear bar 22 of the frame. In order to allow this shaft to be rotated, the ratchet wheel 93 is keyed thereto, while a bifurcated lever 94 is pivoted upon the shaft, as shown in

Figure 5. This lever 94 has a pawl 95 pivoted thereon and passing rearwardly through a slotted plate 96, forward movement of the lever 94 being limited by a chain 97 connected thereto and connected to the slotted plate 96. Thus it will be seen that as the lever 94 is rocked forwardly rotary motion will be imparted to the ratchet wheel 93 to the cam wheel shaft 92, while rearward swinging of the lever 94 will cause the pawl 95 to ride over the surface of the ratchet wheel 93 without rotating the same. As will be seen by referring to Figures 9 and 10, a suitable form of cam wheel 98 may be keyed upon the shaft 92, in this instance the cam wheel being provided by cutting away a part of the periphery of the wheel as shown particularly in Figure 9.

A cam lever 99 is pivoted upon the actuating lever 73 whose rear end normally engages the forward portion of the cam wheel 98 to be held in a lowered position, although such end is urged upwardly by a coiled spring 100 connected to the cam lever 99 and to the actuating lever 73 as shown in Figures 2 and 3. This cam lever 99 has a slide 101 connected thereto from which extends a pin 102. A pin 103 is carried by the ratchet dog 83 in the path of movement of the pin 102. In operation the plow P is held in operative position by the nose 60 of the standard 58 engaging under the end of the arm 56' as shown in Figure 3. At this time the standard is held against accidental swinging by the claw 61 engaging within notches thereof, as explained fully in my prior Patent Number 1,253,961. At this time also the head 80 of the slide 75 is forward of the ratchet dog 83 as shown in Figure 4. Therefore, the tail 85 of the ratchet dog 100 will cause this dog to be held out of engagement with the ratchet wheel 42. Therefore, as the frame moves forwardly and the drive wheel 29 is rotated, rotary motion will be imparted by the chains 37 and 40 and the shafts 35 and 38 continuously to the ratchet wheel 42. At this time, if desired the claws 61 may have a lug 104 carried upon a pivot as illustrated in Fig. 13. An arm 105 may be keyed upon the remaining end of the tube 65 so that when the device is in operative position and the claw is engaged with the notches in the standard 58, the lug 104 may engage the finger 105 and thus hold the gage wheel standard 64 against upward swinging, whereby this coulter wheel may travel in front of the plow to limit the movement of the same into the ground to regulate the depth of the digging action thereof.

It should also be understood that at this time the enlarged portion of the cam wheel 98 should be engaged with the cam lever 99 holding the same downwardly at its rear end and thus causing the slide 101 to be held in a lowered position whereby the pin 102 will 120 125 130

be held out of engagement with and considerably below the pin 103. Thus no interfering action will be had with the ratchet dog 83 which would tend to hold the same in engagement with the ratchet wheel 42.

Now should the plow strike an obstruction which would break the same, as explained in my prior patent, it will be understood from an inspection of the present drawings, the 10 plow will swing forwardly by the arm 56' being curved from engagement with the nose 60 of the standard 58. This pulling of the standard 58 will cause the lower end to move in a counter-clockwise direction, thus forcing the trigger tube 62 forwardly and consequently forcing the trigger 66 forwardly. As seen in Figure 11, when this trigger 66 is forced forwardly, its engagement with the crank shaft 69 will rock the crank shaft 15 20 so that the finger 70 of this crank shaft will pull rearwardly upon the slide 75. As the slide 75 moves rearwardly, obviously its head will likewise move rearwardly and will engage the guide strip 84, thus swinging the 25 ratchet dog 83 into engagement with the ratchet wheel 42 which is rotating as above stated. As the slide is moved rearwardly the spring catch 82 will engage with one of the ratchet teeth 81 of the slide thus holding 30 35 the slide against forward movement so that the head 80 will continue to hold the dog 83 in engagement with the ratchet wheel. As this wheel rotates it will pull the dog forwardly therewith and obviously as the dog is connected to the actuating lever 73, this actuating lever 73 will be pulled forwardly, thus pulling forwardly on the channel 71 and in turn swinging the gage wheel standard 64 toward a vertical position so that the 40 45 plow beam 47 will be supported and will be carried by the movement of the gage wheel 63 over the surface of the ground. This action just stated is simultaneous with the breaking of the plow as stated. In my prior patent it was necessary to stop the plow after it was automatically broken in order that the beam could be lifted and the plow reset. With the present device however, as soon as 50 55 the plow is broken the beam is elevated at its rear end, thus allowing the plow sufficient time to swing back, due to its own weight, causing the arm 56' to again pass the nose, causing the nose to snap under the arm and allow the plow to be again held in a set and operative condition.

As the plow beam 42 continues to move forwardly on the ratchet dog 83, it will be seen that the tail 85 of this ratchet dog will finally strike the lower projecting end of the 60 spring catch thus swinging the catch from engagement with the ratchet teeth 81. Now as a spring 79 engages the finger 70 it will be seen that this spring will pull the finger 70, thus shifting the slide 75 forwardly, 65 whereby the head 80 will be moved from en-

gagement with the guide strip 84 of the ratchet dog 83. As no restraint, therefor, is on the ratchet dog it will immediately swing upwardly from engagement with the ratchet wheel 42 so that further movement of the 70 ratchet dog and the ratchet wheel is discontinued. As no restraint, therefor, is upon the actuating lever 73, the weight of the plow beam and plow being imparted to the standard 64 the gage wheel 63 will cause the 75 standard 64 to swing rearwardly, moving rearwardly on the channel bar 71 and moving the actuating lever 73 rearwardly or until it strikes against the housing 88 of the manually operated lever 87. Therefore, the 80 plow will again enter into the ground to perform its operation. From the operation described, it will be seen that as soon as the plow is automatically broken the beam thereof is practically simultaneously raised at its 85 rear end to allow the plow to swing back to its normal set position and almost simultaneous to this action, the beam is again lowered by the tripping mechanism above explained, whereby the plow may again enter its operative engagement with the ground. Although some little time has been consumed in explaining the operation of the device, which is of the automatic nature, it will be understood that it will be very 90 95 rapid, requiring only probably two or three seconds so that the plow will clear the obstruction it originally struck and will then move forwardly again in proper engagement with the ground.

If for any reason the operator of the device should desire to elevate the plow from engagement with the ground he merely has to swing the handle lever 87 forwardly causing the housing 88 to pull upon the upper end of the actuating lever 73, whereby the actuating lever will pull forwardly upon the channel bar 71 and then swing the gage wheel standard 64 forwardly to cause the gage wheel to support the plow beam and plow. The plow beam may be held in an elevated condition as long as desired, since the operator may cause the detent 89 to engage within selected notches in the quadrants 86 as is apparent. Of course, as soon as the manually operated lever 87 is swung rearwardly, the actuating lever 73 will move rearwardly and thus the channel bar 71 will move rearwardly to allow the gage wheel standard to move rearwardly and thus the plow beam 47 may move downwardly to allow the plow to again engage the ground.

Owing to the broad construction of the frame, as shown in Figure 1 and the manner in which the rear guard 22 is slanted obliquely, it is apparent that several plows may be supported upon the device, side by side as is apparent, for instance, by the disclosure of a pair of cam plates 98. Under 130

such condition however, it will be apparent that the plows will be in oblique arrangement with respect to each other, one advanced slightly forward of the other, according to the number of plows arranged across the rear portion of the frame. In view of the fact that all plows will be of a similar construction and their operating mechanisms would be similar, in order to 10 avoid confusion, only one plow and its operating mechanisms have been disclosed.

Now if the plows have moved across the field without striking any interferences, as the machine arrives at the end of the field 15 and it is desired to remove the plows from engagement with the ground as they arrive at the end of the field the operator oscillates the lever 94 illustrated in Figs. 5 and 6, thus causing the wheel 93 to be rotated and 20 consequently causing the cam shaft 92 to be rotated. As this cam shaft rotates obviously it rotates the cam wheel mounted thereon and as is apparent from an inspection of Figure 3, as the large part of a cam dis- 25 engages its cam lever 99, the spring 100 of such cam lever will swing the same upwardly, causing the slide 101 to move upwardly, whereby the pin 102 will strike the pin 103 of the ratchet dog 83, moving this 30 dog into engagement with the ratchet wheel 42, thus causing the lever 73 to be swung forwardly with the result above explained. Of course, the operator may continue to oscillate the lever 94 and thus the cam shaft 35 will continue to rotate until the cam again engages the cam lever 99, thus forcing the same downwardly, whereby the slide will move downwardly and the pin 102 will dis- 40 engage the pin 103 whereby the ratchet dog will again disengage the ratchet wheel 42, thus allowing the plow beam 47 to again move downwardly at its rear end, for the usual purposes.

It is apparent that when the plow is 45 automatically broken, the rear end of beam 47 will move slightly lateral to also absorb the shock owing to the fact that the brace 49 will pull upon the bolt 53 against the tension of coiled spring 44 as shown in Figure 1 to allow this action although as soon as the obstruction is passed, the spring will again pull upon the bolt 53 to return the foot 51 with normal engagement with foot 46 as above explained.

50 It will therefore be apparent that a very simple and efficient means is provided for operating the coulter wheel standard which will elevate the plow beam automatically when the plow is broken to allow the plow 55 to again snap back into an operative position, after which the coulter wheel standard will again swing to allow the plow to pass into its operative engagement with the ground.

65 This mechanism is automatically operated

as above stated so that the operator may continue to operate the device several plows operating simultaneously with any plow striking an obstruction automatically breaking and then automatically returning to an 70 operative engagement for further operation as stated. The operator may also manually pull the gage wheel standard to a position where the plow will be moved downward in engagement with the ground for when arriving at the end of a row, he may operate the cam shaft 92 to cause automatic lifting of the plows after the cam wheels have disengaged their cam levers. Thus a comparatively simple device of the present nature 80 has been produced which is capable of functioning in several ways for moving the plow from engagement with the ground.

By referring to Figures 14 to 16 inclusive a form of plow which might be used in connection with the present device is illustrated. In this construction of a plow the slide 106 has the usual point 107 upon which the base section 108 of the mold board is carried. This base section is provided with undercut 90 lugs 109 secured thereto in any desired manner. The upper section 110 of the mold board has a wing section 111, this upper section 110 having a plurality of upwardly and rearwardly slanting slots 112 formed there- 95 in. Also a sectional retaining strip 113 is carried by this upper section 110 extending beyond each side of each slot as illustrated clearly in Figure 15. In assembling the device, the upper section 110 is placed upon the base section 108 by the passing of the lugs 109 into the slot 112. The lugs pass through the inner ends of the slots and for this reason are slightly above the sectional strip 113. A locking pin 114 will then be slipped below 100 the lugs and above the strip 113 as shown in Figure 14, and then a retaining lever 115 is employed. This lever is provided with a head 116 at its lower end adapted to fit within a socket 117. The lever assumes the 110 position as shown approximately in Figure 16 with its head 116 in the socket 117, whereupon the lever will be swung forwardly, acting as a fulcrum for forcing the pin 114 far into the engagement with the lugs 109 and a 115 strip 113. The lever may then be swung into a gripping member 118 which will efficiently hold the same against accidental displacement. Of course, the plow, referred to in several figures of the drawing and in general at P may be secured to the lower end of standard 56 in any desired manner.

The foregoing description and the drawings have reference to the preferred or approved embodiment of my invention. It is 120 to be understood however, that I may make such changes in construction and assembly of parts, materials, dimensions, etc., as may prove expedient and fall within the scope of the appended claims.

Having thus fully described my invention, what I claim as new and desire to secure by Letters Patent is:—

1. In a device of the character described, the combination of a frame, a plow beam pivoted upon said frame, and including a plow thereon, means for automatically breaking the plow, a gage wheel standard pivoted upon the plow beam and having a 10 gage wheel, an actuating lever pivoted upon said frame, a bar connecting said standard to said lever, a ratchet wheel rotatable upon said frame, means for driving the ratchet wheel, a ratchet dog carried by said actuating lever, and means operated by said plow-breaking means for moving the dog into engagement with said ratchet wheel subsequent to the release of the plow for causing the lever to move to pull upon said channel 15 bar and swing said gage wheel standard, for elevating the said plow beam.
2. In a device of the character described, the combination of a main frame having a ratchet wheel thereon and means for continuously driving the ratchet wheel, a plow beam pivoted upon said frame and including an automatically broken plow, a gage wheel standard pivoted upon the plow beam, an actuating lever pivoted upon said frame, a 20 bar connecting said standards to said lever, a ratchet dog pivoted upon said lever, and means interconnecting the said automatically broken plow and the said actuating lever operated by the former for automatically moving said ratchet dog in to engagement 25 with said ratchet wheel, and means for releasing said dog from engagement with said ratchet wheel.
3. In a device of the character described, the combination of main frame having a driven ratchet wheel thereon, a plow beam pivoted upon said main frame and including an automatically broken and reset plow, of an actuating lever pivoted upon said main 30 frame and having a ratchet dog pivoted thereon, a gage wheel standard pivoted upon said plow beam and having a gage wheel thereon, a channel bar pivoted to said standard and to said actuating lever, a slide movable within the channel bar and having a 35 head positioned above said ratchet dog, a crank shaft carried by said plow beam and having a finger engaging said slide, a trigger connected to the crank shaft and associated with the automatic plow, whereby when the plow is broken, said trigger will move the shaft to cause said slide to be moved, whereby the head will engage the ratchet dog to move the dog into engagement 40 with the ratchet wheel, thus causing the lever to pull upon the channel bar and swing the gage wheel standard, as and for the purposes set forth.
4. In a device of the character described, the combination of a frame having a driven 45
5. In a device of the character described, the combination of a frame having a driven ratchet wheel, an actuating lever pivoted upon said frame and having a ratchet dog provided with a pin, a plow beam pivoted upon said frame and having a plow, a gage wheel standard, a bar connecting said standard to said actuating lever, a cam lever pivoted upon the actuating lever and having a slide provided with a pin, means for forcing the cam lever in one direction, a cam-shaft having a cam plate thereon, means for rotating the cam-shaft, said cam plate engaging the cam lever for normally holding the same in assembled position, said cam plate being rotated at times to allow the lever to move the slide to allow the cam lever to move the slide whereupon said last mentioned cam will engage the first mentioned pin to swing said ratchet dog into engagement with the ratchet wheel, whereby the actuating lever will be swung to move the bar to swing said gage wheel standard, as and for the purposes set forth.
6. In a device of the character described, the combination of a frame having a plow beam pivoted thereon and provided with a plow, an actuating lever pivoted upon said frame, a gage wheel standard carried by said plow beam, a bar connecting said lever to said standard, quadrants mounted upon said frame upon each side of said actuating lever, a manually operated lever pivoted upon said frame, and having detent means for engaging said quadrants to hold the manually operated lever in an adjusted position, said manually operated lever being adapted to be swung to swing said actuating lever whereby the actuating lever will

draw upon the bar to swing said gage wheel standard, as and for the purposes set forth.

7. In a device of the character described, the combination of a frame, a bracket carried upon said frame and consisting of a body having a lip at one end and a projection at the remaining end, the projection terminating in an angular foot, a plow beam having a plow, said plow beam being pivoted upon said lip, a brace connected to said plow beam and having a foot engaging said first mentioned foot and spring pressed means for yieldably holding the last mentioned foot in engagement with the first mentioned foot, whereby when strain is brought to bear upon the plow, said beam may swing laterally, as and for the purposes set forth.

8. In a device of the class described the combination of a frame, a plow beam pivoted to said frame including a plow carried thereby, a gage wheel standard and gage wheel pivoted to the beam, a lever pivoted on the frame, a bar connecting said lever with the gage wheel standard and slidable means

movable reversely with respect to said bar, whereby the lever is actuated to cause the said beam to be elevated when the plow strikes an obstruction.

9. In a device of the character described the combination of a frame, a plow beam pivoted to said frame including a plow carried thereby, a gage wheel standard and gage wheel pivoted to the beam, a continuously rotatable ratchet wheel on the frame, a lever and dog mechanism cooperating with said ratchet wheel, a bar connecting said lever with the gage wheel standard, and means reversely slidable with respect to the bar whereby the ratchet and dog mechanisms are operated to permit the standard to be raised and lowered when the plow strikes an obstruction.

In testimony whereof I affix my signature in presence of two witnesses.

EMIL GRIMSRUD.
